UNITED STATES PATENT OFFICE.

DAVID D. BUICK, OF DETROIT, MICHIGAN.

DESIGN FOR A BATH-TUB.

SPECIFICATION forming part of Design No. 29,677, dated November 15, 1898.

Application filed October 14, 1898. Serial No. 693,567. Term of patent 14 years.

To all whom it may concern:

Be it known that I, DAVID D. BUICK, a citizen of the United States, residing at Detroit, in the county of Wayne and State of Michigan, have invented and produced a new and original Design for a Bath-Tub, of which the following is a specification, reference being had therein to the accompanying drawings.

Figure 1 is a perspective view showing one end of the tub. Fig. 2 is a top plan view of the tub. Fig. 3 is a longitudinal section thereof.

A is a bath-tub having at one end an inclined wall B and at the opposite end the substantially vertical wall C.

15 In the central up portion of the wall C is formed the niche or recess D.

E is the rim, which curves around the niche D and has the swells F at the ends of the niche.

The leading feature of the design comprises 20 the shape and configuration of the bath-tub provided with the niche D in the end wall of the tub.

What I claim as my invention is—

The design for a bath-tub substantially as 25 herein shown and described.

In testimony whereof I affix my signature in presence of two witnesses.

DAVID D. BUICK.
